UNITED STATES PATENT OFFICE.

MICHAEL J. MILMOE, OF CHICAGO, ILLINOIS, ASSIGNEE TO F. B. REDINGTON COMPANY, OF CHICAGO, ILLINOIS, A CORPORATION OF ILLINOIS.

BLANK-FEEDING MECHANISM.

Application filed December 12, 1925. Serial No. 74,969.

- This invention relates to mechanism for feeding blanks or sheets and is especially adapted to feed carton blanks to mechanism for forming the blanks into cartons.
- 5 The object of the invention is to provide a sheet feeding mechanism which will be accurate and reliable in its operation, which will be of improved construction, and which will operate on blanks of irregular shape.
- 10 The invention is exemplified in the combination and arrangement of parts shown in the accompanying drawings and described in the following specification, and it is more particularly pointed out in the appended 15 claims.
- In the drawings,
- Fig. 1 is a top plan view of a blank feeding mechanism embodying one form of the present invention.
- 20 Fig. 2 is a side elevation of the mechanism shown in Fig. 1.
- Fig. 3 is a top plan view of a detail of construction.
- 25 Fig. 4 is an end elevation of the parts shown in Fig. 3.
- Fig. 5 is a rear elevation of the mechanism shown in Figs. 1 and 2.
- 30 Fig. 6 is a vertical section substantially on line 6—6 of Fig. 1.
- Fig. 7 is an elevation of the mechanism for separating the blanks from the bottom of the stack.
- 35 Fig. 8 is an elevation of a detail of construction.
- Fig. 9 is a top plan view of a portion of the mechanism including the stripper.
- 40 Fig. 10 is an elevation of a carton blank for which the embodiment of the invention shown in the drawings is adapted.
- 45 In my prior application Serial No. 410,401½, I have shown a form of carton forming and filling mechanism to which unfolded carton blanks are supplied, the blanks being carried to the carton forming mechanism by a conveyer upon which they are placed by hand. The present invention is designed especially to cooperate with the carton forming mechanism shown in the aforementioned application, and is arranged to 50 supply the blanks automatically to the forming mechanism. It will be understood, however, that the invention is not limited to the particular machine to which the blanks are fed.
- The mechanism as shown in the drawings is supported on a frame 11, which may be the rear end of the frame of a carton forming and filling machine. The machine is provided with a main drive shaft 12, which operates a sprocket chain 13 extending upwardly to a sprocket wheel 14 on a jack shaft 15. The shaft 15 is provided with a bevel gear 16, which meshes with a cooperating gear 17 on a shaft 18 extending transversely of the machine and arranged to drive parts of the blank feeding mechanism. The blanks as shown at 19, Fig. 10, are irregular in shape comprising a longitudinal strip and flaps disposed at opposite sides thereof. The blank is folded into the form of a carton by folding on the transverse lines 20. The flaps are then in position to form closures for the ends of the cartons. The blanks are held in a magazine comprising end walls 22 and 23 which are provided with supporting strips 24 and 25, respectively, which are bent inwardly at their lower edges to form supporting flanges or ledges 26 and 27. The ends of the cartons rest on the ledges 26 and 27, and forwardly projecting flaps 28 engage an inclined plate 29 supported on a bracket 30 extending forwardly from the side wall 22. The flaps 28 are bent slightly upwardly and the lower edge of the plate 29 terminates above the ledges 26 and 27, so that the lowermost flaps will pass the lower edge of the plate 29. A suction head 31 is arranged to engage the rearwardly extending flap 32 of the lowermost carton blank and draw it downwardly away from the other blanks, as shown in Fig. 7. This suction head is formed rigidly on the end of an arm 33 having an air-duct 34 extending longitudinally thereof. The head 31 is provided with a transverse cylindrical passage 35 having a rotary valve 36 disposed therein. A passage 37 extends from the cylindrical opening 35 to the contact surface of the head. The rotary valve 36 has cut-away portions 38 and 39 on opposite sides thereof arranged to connect the passage 37 alternately with the air-duct 34 and with a vent opening 40. An arm 41 is connected to the end of the valve 36 and is provided with a pin 42 extending into a cam-shaped opening 43 in a plate 44. When the head 31 is swung upwardly to engage the lower surface of a blank the opening 37

will be connected to the air duct 34 by means of the port 39. As the arm 33 swings downwardly the pin 42 will strike the lower edge of the cam opening 43 and rotate the arm 41 into the position shown in Fig. 8, so that the port 38 will connect the opening 37 with atmosphere through the port 40. The arm 33 is connected at its end opposite the suction head 31 to a rock shaft 45, which is 10 provided with a central duct 46 communicating with the air duct 34 in the arm 33. The rock shaft 45 extends through a suction chamber 47 and forms a tight connection with the walls of the chamber. The duct 46 15 is provided with an opening into the suction chamber 47 through a pipe line 48, which communicates with a pump 49. The rock shaft 45 projects from the side of the suction chamber 47 and carries an arm 50 20 having a cam roller 51 thereon, which travels in a cam groove 52 in a wheel 53. The wheel 53 is mounted on the shaft 18 so that rotation of the shaft will oscillate the arm 33 and move the suction head 31 up and down. 25 When the suction head is raised it will engage the lower face of the lowermost carton blank and on the return movement will draw the flap 32 downwardly into the position shown in Fig. 7. Before the suction is released by the valve 36 a stripper will be moved between the upper face of the lowermost carton blank and the other blanks in the stack. This stripper comprises a pair of spaced plates 54 and 55, shown more 30 clearly in Figs. 6 and 9. These plates are supported on the swinging frame 56 having forwardly extending ribs 57 and 58 for supporting the plates 54 and 55, respectively. The frame 56 is supported on a pair of pins 35 59 and 60, which are journaled in bearings 61, 62, 63 and 64 extending upwardly from the frame 56. The pin 59 is supported on a rocker frame 65 comprising a pair of arms 66 and 67 connected by cross bars 68 and 40 69 pivoted at their lower ends on a shaft 69 supported by brackets 70 mounted on the frame 11. The shaft 60 is carried on an arm 71 journaled at 72 on the bracket 70. It will be seen that the frame 65 and the arm 71 provide 45 a parallel movement for the stripper frame 56. The frame 65 is oscillated by a link 73, which is connected at 74 to the frame 65 and at 75 to an arm 76. The arm 76 is pivotally mounted at 77 on the frame of the machine 50 and is provided with a cam roller 78, which 55 engages a cam groove 79 on the cam wheel 80 mounted on the shaft 18. Rotation of the shaft 18 oscillates the arm 76, which motion is transmitted through the link 73 to the 60 frame 65 and stripper frame 56. The link 73 is adjustable to permit adjustment of the position of the stripper frame. The stripper will move forwardly from the position shown in Fig. 7 and will engage the upper 65 surface of the carton blank, extracting the

carton from the magazine and carrying it downwardly beneath the plate 54 until the stripper plate has reached the position shown in Fig. 6.

In order that the lowermost carton may be easily extracted from beneath the other cartons in the stack it is desirable to lift the stack of cartons at the time that the lowermost carton is extracted. This result is secured by means of a pair of lifters comprising slide bars 81 and 82. These bars are provided with grooves 83 and 84, which slidably engage pins 85 and 86 on supporting brackets 87 and 88 respectively. The lifters are provided with nose pieces 89 and 90 arranged to extend beneath the edges of the carton blanks. The lifter 81 is in the rear of the lifter 82 for the reason that the lifter 81 engages the rearwardly projecting end flaps while the lifter 82 is positioned in registration with the edge of the main body portion of the carton. The lifter 89 carries a roller 91 arranged to engage the upper edge of a cam plate 92 supported on the rib 57 of the stripper frame 56. In like manner the lifter 82 is provided with a roller 93 arranged to engage a cam plate 94 on the supporting rib 58. As the stripper frame swings forwardly the cam plate will carry the lifter forwardly against the rear edge of the carton and the rollers will travel on the upper faces of the cam plates to lift the cartons and free the lowermost blank so that it may be withdrawn from the ledges 26 and 27. The lifters 81 and 82 are provided with cam faces 95 and 96, which engage cooperating fixed stops 97 and 98 to swing the lifters forwardly as they are raised by the cam plates.

A reciprocating slide is provided for receiving the carton blanks as they are extracted from the magazine and for moving them forwardly into position to be engaged by the carton forming mechanism. This slide comprises a bar 100 having a longitudinal groove provided with rack teeth 101 for meshing with a gear 102. The gear 102 is mounted on a shaft 103, which carries a pinion 104 meshing with a rack 105. The rack 105 is provided with a cam fork 106 at its lower end which engages the drive shaft 12 and which carries a cam roller 107 engaging a cam groove 108 in a cam wheel 109 secured to the shaft 12. By this mechanism reciprocation is imparted to the bar 100. A plate 110 is secured to the rear end of the bar 100 and carries a pivot pin 111 having a forwardly extending arm 112 mounted thereon. The forward end of the arm 112 is provided with a cross piece 113 and forwardly projecting blades 114 and 115. The blades 114 and 115 underlie the plates 54 and 55, respectively. A link 116 is pivotally connected at 117 to the arm 112 and the lower end of the link is provided with a slot 118, which engages a pin 119 120

on the lower end of the arm 67 of the frame 65. When the frame 65 is swung rearwardly by the pin 119 will engage the upper end of the slot 118 and raise the arm 112 and the blades 114 and 115 into the position shown in Fig. 7. The blades will be frictionally retained in this position by a friction clamp shown more clearly in Figs. 3 and 4. This clamp comprises a bracket 120 mounted on the frame plate 121. A pair of ears 122 extend laterally from the bracket 120 and a jaw member 123 is pivotally mounted at 124 between the ears 122. A spring 123' closes the upper end of the jaw member against the arm 112 and clamps the arm between the jaw member 123 and an upwardly projecting flange 125 on the bracket 120. This will retain the blades 114 and 115 in their uppermost position until they are forced downwardly by the pressure of the stripper against the extracted carton blank. In this way the blades serve to support the blank against the lower face of the stripper and prevent displacement of the blank during its downward movement from the lower end of the stack. The rack 100 remains stationary during the downward movement of the blades. This movement will position the rear edge of the carton in front of the forward ends of a pair of fingers 126. These fingers are supported on a transverse plate 127 secured to the front edge of the plate 110. When the carton blank has been moved to its lowermost position the rack bar 100 will be moved forwardly by the gear 102 and the carton blank will be projected forwardly from beneath the stack by means of the fingers 126, the blank being supported in its forward movement by the blades 114 and 115. The blades and fingers will then be withdrawn and the blank will be left in position for further manipulation by any suitable mechanism.

I claim:

1. Apparatus for feeding blanks comprising a magazine having supporting ledges for a stack of blanks, a suction head for engaging a projecting portion of the lowermost blank of the stack and for moving said projecting portion downwardly, a stripper arranged to enter the space between the said projecting portion and the remaining blanks in said magazine to extract said blank from said magazine, and a lifter operated by said stripper to raise the remaining blanks in said magazine to permit said lowermost blank to be easily withdrawn from said supporting ledges.

2. Blank feeding mechanism comprising a support for a stack of blanks, a suction head for engaging the lower face of the bottom blank in said stack, a pivoted arm for supporting said suction head, said head having a contact face directed laterally relative to said arm to engage said blank when said

arm is swung laterally in one direction, means for moving said arm on its pivot to swing said head toward and from said stack, said arm having an exhaust air duct therein, a valve for controlling said air duct, an operating lever carried by and movable with said arm and connected with said valve, and means for engaging said operating lever to move said valve when said head is swung by said arm.

3. Apparatus for feeding blanks comprising a support for a stack of blanks, a suction head for engaging the blanks in said stack, means for moving said head toward and from said stack, a valve for controlling the operation of said head, an arm connected with said valve, and extending transversely of the direction of movement of said arm, and a stationary cam for engaging said arm to operate said valve when said head is moved relative to said stack, said cam having opposed abutment portions between which said arm is oscillated by the movement of said head.

4. Apparatus for feeding blanks comprising a support for a stack of blanks to be fed, a suction head for engaging the blanks in said stack, a pivoted arm for supporting said suction head having an air duct communicating with said suction head, a spindle on which said arm is mounted having an air duct therein communicating with the duct in said arm, an exhaust chamber through which said spindle passes, the air duct in said spindle communicating with the interior of said exhaust chamber, and means for exhausting air from said exhaust chamber.

5. Apparatus for feeding blanks comprising a support for a stack of blanks to be fed, a suction head for engaging the blanks in said support, an arm for supporting said suction head having an air duct therein communicating with said head, a valve for controlling the passage of air through said air duct, a spindle on which said arm is mounted having an air duct therein communicating with the air duct in said arm, an exhaust chamber into which said spindle extends and with which the air duct in said spindle communicates, means for exhausting air from said exhaust chamber, means for swinging said arm about the axis of said spindle, an operating lever connected with said valve, and a stationary cam for engaging said operating lever to operate said valve when said arm is swung upon the axis of said spindle.

6. Apparatus for feeding blanks comprising a support for a stack of blanks to be fed, means for bending a portion of the endmost blank in said stack away from the other blanks in said stack, a stripper plate, and means for moving said plate into the space thus provided between the endmost

- blank and the other blanks in the stack and for moving said plate transversely of the plane thereof away from the blanks in said stack to extract said endmost blank from said supporting means.
7. Blank feeding mechanism comprising a support for a stack of blanks, means for separating a portion of the endmost blank in said stack from the other blanks therein, 10 a stripper plate, a lifter, a cam rail connected with said stripper plate arranged to engage said lifter, and means for moving said stripper plate and cam rail toward said stack to cause said stripper plate to extract the endmost blank from said stack and to cause said cam rail to engage said lifter and shift the other blanks in said stack.
8. Mechanism for feeding blanks having projecting flaps thereon, said mechanism comprising a support for a stack of blanks, means for engaging a projecting flap on the endmost blank in said stack and for bending said flap away from the remaining blanks in said stack, a stripper plate arranged to enter the space between said flap and said remaining blanks, and a second stripper arranged to enter the space between said endmost blank and the other blanks in said stack subsequent to the entry of said first named stripper.
9. Mechanism for feeding blanks comprising a magazine for supporting a stack of blanks, means for engaging the lowermost blank in said stack and bending a portion thereof downward, a pair of strippers arranged to enter the space between said lowermost blank and the other blanks in said stack, means for moving said strippers simultaneously toward said stack, said strippers being positioned to enter the space between the blanks of said stack successively.
10. Mechanism for feeding blanks comprising a magazine for supporting a stack of blanks, means for engaging the lowermost blank in said stack and bending a portion thereof downwardly, a stripper arranged to enter the space between said bent portion and the other blanks in said stack to produce further downward movement of said blank, a second stripper arranged to enter the space between said lowermost blank and the other blanks in said stack subsequent to the entry of said first named stripper, and lifters cooperating with said strippers to lift the remaining blanks in said stack.
11. Blank feeding mechanism comprising a support for a stack of blanks, means for bending one edge of the lowermost blank in said stack downwardly, a stripper arranged to enter the space above the downwardly bent portion of said blank, a cam rail connected with said stripper and movable therewith, a lifter having a nosepiece for engaging the blanks in said stack, a roller on said lifter for engaging said cam rail, and a guide for said lifter permitting vertical and lateral movement thereof when engaged by said cam rail.
12. Blank feeding mechanism comprising 70 a magazine for supporting a stack of blanks, means for bending the edge of the lowermost blank in said stack downwardly, a stripper arranged to enter the space thus provided above said lowermost blank, and means for moving said stripper horizontally toward said stack and downwardly away from the bottom thereof to extract said lowermost blank from said stack.
13. Blank feeding mechanism comprising 80 a magazine for supporting a stack of blanks, means for bending a portion of the endmost blank in said stack away from said stack, a stripper plate for entering the space between said bent portion and said stack, 85 guides for holding said stripper plate in substantially parallel positions, and means for moving said stripper plate in the direction of the plane of said blanks and also transversely to the plane thereof to extract 90 said lowermost blank from said stack.
14. Mechanism for feeding blanks comprising a magazine for supporting a stack of blanks to be fed, means for separating a portion of the endmost blank from said 95 stack, a stripper, and parallel motion mechanism for moving said stripper between said endmost blank and the other blanks in said stack and transversely to the plane of said blanks away from said stack to extract said 100 endmost blank from said stack.
15. Blank feeding mechanism comprising a magazine for supporting a stack of blanks to be fed, a stripper for engaging the inner face of the endmost blank of said stack, 105 means for engaging the outer face of said blank, and means for moving said stripper away from said stack to extract said endmost blank therefrom while held between said stripper and said engaging means. 110
16. Blank feeding mechanism comprising a support for a stack of blanks, means for separating a portion of the endmost blank from said stack, a stripper arranged to enter the space between said endmost blank and said stack, a support for engaging said blank on the face thereof opposite said stripper, means for moving said stripper away from said stack to extract said endmost blank therefrom, and yielding means for holding 115 said engaging means against said blank during the movement of said stripper.
17. Blank feeding mechanism comprising a magazine for supporting a stack of blanks, a suction device for engaging the lowermost 120 blank in said stack and bending a portion thereof downwardly, a stripper arranged to enter the space above said downwardly bent portion, a supporting finger arranged to engage the lower face of said endmost blank, 125 130

- means for moving said stripper downwardly to extract said blank from said magazine, and a friction brake for retaining said finger against the lower face of said blank during the downward movement thereof.
18. Blank feeding mechanism comprising a magazine for supporting a stack of blanks, a stripper frame for extracting the endmost blank from said stack, parallel motion mechanism for operating said stripper frame, and a forwarding device for receiving the blank from said stripper frame and moving it away from said stack.
19. Blank feeding mechanism comprising a magazine for supporting a stack of blanks to be fed, means for bending a portion of the endmost blank in said stack, a stripper for entering the space between said bent portion and stack, means for imparting arcuate movement to said stripper to extract said blank from said stack, a forwarding device for receiving the blank from said stripper, and means for imparting straight line movement to said forwarding device.
20. Mechanism for feeding blanks comprising a magazine for supporting a stock of blanks to be fed, a suction device for bending a portion of the lowermost blank in said stack downwardly, a stripper frame for entering the space above the bent portion of said blank, a pair of arms for supporting said stripper frame and for imparting arcuate parallel motion thereto, a forwarding device for receiving the blank from said stripper frame, means for imparting straight line movement to said forwarding device, a frictionally held movable support connected with said forwarding device, and means for moving said support into engagement with the endmost blank in said stack prior to the 40 operation of said stripper frame thereon.
21. Blank feeding mechanism comprising a magazine for supporting a stack of blanks to be fed, a forwarding device positioned below said magazine, means for imparting 45 reciprocating movement to said forwarding device, a supporting member carried by said forwarding device and movable upwardly therefrom into engagement with the lowermost blank in said magazine, and means for 50 extracting said lowermost blank from said magazine and moving it downwardly on said forwarding device while engaged by said supporting means.
22. Blank feeding mechanism comprising 55 a magazine for supporting a stack of blanks to be fed, means for bending the edge of the lowermost blank in said stack downwardly, a stripper for entering the space above the bent portion of said blank, means for imparting horizontal and vertical movement to said stripper to extract said blank from said magazine, a horizontally movable forwarding device for receiving the blank from said stripper, a supporting finger connected with 60 said forwarding device, lost motion connection between said finger and stripper for raising said finger into position against the lower face of the lowermost blank in said magazine, and friction means for yieldingly 65 holding said finger against said lowermost face when said blank is extracted from said magazine.
- In testimony whereof I have signed my name to this specification on this 8th day of 70 December, A. D. 1925.
- 75

MICHAEL J. MILMOE.
